DESCRIPTION

FIG. 1 is a top perspective view of a container showing our new design;

FIG. 2 is a front elevation view thereof, the left side, right side and rear elevation view being identical;

FIG. 3 is a top plan view thereof; and,

FIG. 4 is a bottom plan view thereof.

The ornamental design which is claimed is shown in solid lines in the drawings. The broken lines in the drawings are for illustrative purposes only and form no part of the claimed design.
